ROD AND WIRE HANDLING MECHANISM

Frederick A. Westphal, Kansas City, Mo., assignor
to Sheffield Steel Corporation, Kansas City,
Mo., a corporation of Delaware

Application March 1, 1935, Serial No. 8,894

11 Claims. (Cl. 242—128)

This invention relates to rod and wire handling mechanism for transporting coiled bundles of rods or wire to a wire working machine and for holding the bundles while a rod or wire is pulled therefrom in response to the demands of the machine, and has for its principal object to provide an apparatus of this character with mechanism to insure withdrawal of the convolutions in single consecutive order.

10 In accomplishing this and other objects of the invention, as hereinafter pointed out, I have provided improved details of construction, the preferred form of which is illustrated in the accompanying drawing, wherein:

15 Fig. 1 is a perspective view of a rod and wire handling apparatus embodying the features of the present invention.

Fig. 2 is a side elevation of the hair pin hook for impalingly supporting the coiled bundles of rods or wire and equipped with my improved means for regulating withdrawal of the convolutions of rods or wire and showing one of the convolutions about to be released from the hook.

20 Fig. 3 is a similar view after the convolution has been withdrawn and the succeeding convolution is being separated from the remaining convolutions preparatory to withdrawal from the hook.

Fig. 4 is an enlarged perspective view of the 25 release and separating members for controlling withdrawal of the convolutions.

Referring more in detail to the drawing:

1 I designates a tram rail on which is mounted a carriage 2 suspending a hair pin hook 3 for 30 transporting coiled bundles of rods or wire 4 to a wire working machine, for example, a wire drawing apparatus 5.

The hair pin hook 3 is of conventional design and includes upper and lower horizontal arms 6 and 7 of I beam construction and connected at their rear ends by a vertical bar portion 8. The upper arm 6 is suspended from the carriage 3 which includes hangers 9 and 10 having wheeled support on the tram rail 1. The lower arm provides a support for the bundles of rods or wire 4 which are sleeved or impaled thereon over the free end 11 of the arm so that the lower portions 13 of the bundles hang free of the support and the convolutions 13 thereof are free to be withdrawn off the end 11 in response to demand of the wire drawing machine.

The wire drawing machine includes a drawing bench 14 supporting a reducing die 15 and a rotating block or drum 16 which draws the rod or wire strand 17 through the die and which winds

the reduced wire strand 18 into a coiled bundle 19. The rod or wire strand upon being led from the hook is passed through a guide and safety ring 20 carried on the end of an arm 21 for actuating a switch mechanism or the like (not shown) to shut down operation of the wire drawing machine in case the rod or wire should become entangled.

When the rod or wire is being pulled off the bundles 4, the convolutions 13 would ordinarily strip off the end 11 of the arm 7 in a state of entanglement, and means is, therefore, provided to retain the convolutions on the arm and insure their orderly withdrawal in single consecutive order according to demand of the wire working machine as now to be described.

22 designates a primary clicker including a substantially U shaped fork 23 provided with downwardly curved tines 24 and 25 engaging the side edges 26 and 27 of the arm. The tines 24 and 25 slightly converge in the direction of the connecting portion 28 of the fork so that they have support on the arm and to limit the extent of overlap of the ends of the tines. The fork is carried at the lower end of an inclined 20 and slightly offset shank 29 which has its upper 25 end attached to a yoke-shaped clip 30 that is pivoted to the upper arm by means of a cross pin 31.

In order to accommodate the clip, the lower flange of the upper arm is cut away as at 32 so 30 that the ears 33 and 34 of the clip straddle the web 35 of the arm.

To facilitate construction of the clicker, the shank 29, clip 30 and fork 23 are preferably separate parts formed of bar stock shaped to form 35 the respective parts and welded together as shown at 36 and 37. The pivot 31 of the clip is located in such spaced relation with the front ends of the hook arms that the fork portion thereof engages the lower arm at a point spaced rearwardly 40 from the end thereof to form a supporting surface 38 for a purpose later described.

The clicker 22 is thus supported in engagement with the arm 7 so that it forms a stop to detain withdrawal of the convolutions, but is adapted 45 to raise under pull of the rod or wire strand to pass the convolutions 13 thereunder; however, when the fork 23 is raised by pull of one of the convolutions 13, the succeeding convolution is likely to slip thereunder and be pulled off the end of 50 the arm before the clicker can again drop into stopping engagement.

Therefore, in order to guard against withdrawal of the second coil or convolution 13 from the supporting end of the arm, I provide a secondary 55

clicker 39 which has gravity bearing on the surface 36 to form a stop to prevent complete withdrawal of the second convolution but allow removal of the first convolution. The secondary 5 clicker includes a spade shaped plate 40 having a straight lower edge 41 bearing against the arm at a point spaced from the bearing point of the fork 23 of the primary clicker and which has a rod shaped shank 42 pivoted to a yoke shaped 10 clip 43 carried on the shank of the primary clicker. The clip 43 is welded to the shank and has forwardly projecting ears 44 and 45 for engaging the sides of an eye 46 that is formed on the end of the rod shaped shank 42, the shank being pivoted on a pin 47 extending through the ears and through the eye as shown in Fig. 4. The shank 42 is preferably of sufficient length so that the secondary clicker is supported at a slightly greater 15 incline than the primary clicker 22.

20 The primary and secondary clickers are thus connected with each other and are mounted on the arms of the hook as a single unit.

The clicker units thus described may be constructed of different weights and may be interchangeable 25 with each other depending upon the size of the rods or wire and the speed at which the convolutions are withdrawn by the wire working machine.

In loading the hook, the primary and secondary 30 clickers are raised to permit passage of the bundles of rods or wire 4 over the arm 7, or a clicker unit of proper weight may be attached subsequently to the hook preparatory to drawing wire.

After the bundles 4 are in place, the clickers 35 22 and 39 are dropped to position for support on the lower arm 7 of the hook. The hook is then moved along the tram rail 1 to carry the bundles of rods or wire into operative relation with the wire working machine 5.

40 After arriving at the machine, the rod or wire strand 17 is threaded through the eye of the guide and safety ring 20, through the reducing die 15 and engaged with the rotary block or drum 16 of the wire drawing machine.

45 As the block 16 is rotated to draw the rod or wire through the die 15, the rod or wire is pulled from the bundle in such a manner that the convolutions move over the upper face of the arm into engagement with the fork 23 and primary 50 clicker bar 22. As the wire tightens, the first coil will engage the tine 25 and raise the clicker bar from engagement with the arm to permit the rod or wire to pass thereunder. Immediately upon passing of the rod or wire, the clicker bar 55 will return to its normal position with the convolution extending across the arm between the tines 24 and 25 of the fork. Continued movement of the strand will then bring the coil into engagement with the other tine 24 to again raise the 60 clicker bar upon its pivot to allow complete passage of a convolution.

Due to the springy nature of the rods or wire, it sometimes happens that two or more convolutions escape past the primary clicker bar while 65 the first convolution is being moved thereunder. However, the secondary clicker bar 39 retains its engagement with the upper face of the arm to prevent disarrangement of the convolutions 13 from the supporting surface 38 and the extra 70 coils will then be entrapped between the primary and secondary clicker bars.

Upon continued pull of the wire strand, the first circumvolution will be caused to move under the lower edge 41 of the secondary clicker bar 75 which pivots upwardly under pull of the drum 16

to permit passage of the convolution from the free end of the arm.

Immediately upon passage of the convolution, the secondary clicker bar 39 will again drop into position to detain any succeeding convolution that 5 may have passed the primary clicker 22. After the first convolution has been drawn into the wire working machine, a second convolution will follow in a similar manner and so on in single consecutive order. In case that two of the convolutions 10 should pass the primary clicker bar, it is very doubtful that both of them will be pulled from under the secondary clicker bar.

With the construction thus described, I am enabled to provide the precaution that not more 15 than one convolution will be removed from the hook upon withdrawal of any one single coil.

From the foregoing, it is apparent that I have provided a clicker mechanism which insures withdrawal of the convolutions in single consecutive 20 order and thereby prevents entanglement of the convolutions.

What I claim and desire to secure by Letters Patent is:

1. In an apparatus of the character described, 25 means for suspending a coiled bundle of rods of wire, and primary and secondary clicker members carried by said suspending means and cooperating with said suspending means to regulate successive withdrawal of convolutions from 30 said bundle from off said suspending means, one of said clicker members having double contact with the suspending means to permit alternate engagement thereof with said convolutions during withdrawal of said convolutions from the 35 bundle.

2. In an apparatus of the character described, means for suspending a coiled bundle of rods or wire, primary and secondary clicker members having relatively eccentric mounting to permit 40 differential pivotal movement of said members to and from bearing contact with the suspending means for retarding withdrawal of successive convolutions of the rods or wire from said suspending means and for regulating successive 45 withdrawal of convolutions from said bundle from off said suspending means.

3. In an apparatus of the character described, means for suspending a coiled bundle of rods or wire, a clicker member mounted on the suspending 50 means for controlling withdrawal of convolutions from said bundle, and other means carried by and bearing upon the suspending means for selectively detaining convolutions passing said clicker member, said other means being yieldable to pass the detained convolutions 55 between the same and said suspending means.

4. In an apparatus of the character described, a hook including an upper arm and a lower arm for impaling a coiled bundle of rods or wire, a primary clicker pivoted to the upper arm and having a fork engaging the lower arm to yieldingly retain convolutions drawn from said coil on the lower arm, and a secondary clicker for controlling withdrawal of convolutions passing 65 the primary clicker.

5. In an apparatus of the character described, a hair pin hook having an upper arm and a lower arm for impaling a coiled bundle of rods or wire, a primary clicker pivoted to the upper arm and having a fork engaging the lower arm to yieldingly retain convolutions drawn from 70 said coil on the lower arm, and a secondary clicker pivoted to the primary clicker and having a plate portion bearing on said lower arm 75

for controlling withdrawal of convolutions passing the primary clicker.

6. In a carrier of the character described, a hair pin hook having an upper arm and a lower arm for impaling a coiled bundle of rods or wire, a primary clicker having a shank pivotally connected with the upper arm and provided with a fork having tines engaging side edges of the lower arm to control movement of convolutions along said arm and yieldable for passage under the tines, and a secondary clicker having a shank pivoted to the first named shank and provided with a plate member having bearing contact on said lower arm for controlling withdrawal of convolutions passing the tines of the primary clicker.

7. In an apparatus of the character described, a travelling carrier including a hair pin hook having an upper arm suspended from said carrier and a lower arm for impaling a coiled bundle of rods or wire, a primary clicker pivoted to the upper arm and having a fork engaging the lower arm to yieldingly retain convolutions drawn from said coil on the lower arm, and a secondary clicker pivoted to the primary clicker for controlling withdrawal of convolutions passing the primary clicker.

8. In an apparatus of the character described, a travelling carrier including a hair pin hook having an upper arm suspended from said carrier and a lower arm for impaling a coiled bundle of rods or wire, a primary clicker pivoted to the upper arm and having a fork engaging the lower arm to yieldingly retain convolutions drawn from said coil on the arm, and a secondary clicker pivoted to the primary clicker and having a plate portion bearing on said lower arm for controlling

withdrawal of convolutions passing the primary clicker.

9. In combination with a travelling carrier including a hair pin hook having an upper arm suspended from the carrier and a lower arm for impaling a coiled bundle of rods or wire, a primary clicker having a shank pivotally connected with the upper arm and provided with a fork having tines engaging side edges of the lower arm to control movement of convolutions along said arm for passage under the tines, and a secondary clicker having a shank pivoted to the first named shank and provided with a plate member having bearing contact on said lower arm for controlling withdrawal of convolutions passing the tines of the primary clicker.

10. In an apparatus of the character described, a hair pin hook having an upper arm and a lower arm for impaling a coiled bundle of rods or wire, a primary clicker pivoted to the upper arm and having double contact with the lower arm whereby the primary clicker has alternate engagement with convolutions withdrawn from said coiled bundle, and a secondary clicker having bearing contact on said lower arm for controlling withdrawal of convolutions passing the primary clicker.

11. In an apparatus of the character described, a hair pin hook having an upper arm and a lower arm for impaling a coiled bundle of rods or wire, a primary clicker pivoted to the upper arm and having engagement with the lower arm for yieldingly retaining convolutions withdrawn from said coiled bundle, and a secondary clicker pivoted to the primary clicker and having bearing support on the lower arm for controlling withdrawal of convolutions passing the primary clicker.

FREDERICK A. WESTPHAL.
